Des. 206,316
Patented Nov. 22, 1966

206,316

OFFSHORE STORAGE TANK

Robert S. Chamberlin, Western Springs, Donald C. Stafford, Hinsdale, and Charles A. McDonald, Palos Heights, Ill., assignors to Chicago Bridge & Iron Company, Oak Brook, Ill., a corporation of Illinois

Continuation of design applications Ser. No. 84,057, Mar. 3, 1965, and Ser. No. 84,461, Mar. 26, 1965. This application Nov. 24, 1965, Ser. No. 516

Term of patent 14 years

(Cl. D91—1)

FIGURE 1 is a perspective view of an offshore storage tank showing our new design;

FIGURE 2 is a plan view thereof;

FIGURE 3 is a modified form thereof; and

FIGURE 4 is a top plan view of the modified form of FIGURE 3.

This application is a continuation of our copending applications Serial Nos. D.84,057, filed March 3, 1965 and D.84,461, filed March 26, 1965, both now abandoned.

We claim:

The ornamental design for an offshore storage tank, as shown and described.
